(57) **CLAIM**

I claim the ornamental design for an electrical connector, as shown and described.

DESCRIPTION

FIG. 1 shows a bottom, left side perspective view of an electrical connector;

FIG. 2 shows a rear view of FIG. 1;

FIG. 3 shows a left side view of FIG. 1;

FIG. 4 shows a front side view of FIG. 1;

FIG. 5 shows a bottom side view of FIG. 1;

FIG. 6 shows a right side view of FIG. 1; and,

FIG. 7 shows a top side view of FIG. 1.

The broken lines in the drawings illustrate portions of the electrical connector that form no part of the claimed design.

1 Claim, 7 Drawing Sheets
